UNITED STATES PATENT OFFICE

LEE R. HARTLEY, OF FORT WAYNE, INDIANA, ASSIGNOR TO S. F. BOWSER & COMPANY, INC., OF FORT WAYNE, INDIANA, A CORPORATION OF INDIANA

INTERLOCKING AND SIGNAL MECHANISM FOR LIQUID DISPENSERS

Application filed April 17, 1926. Serial No. 102,661.

This invention relates to dispensing devices for gasoline or other liquids, and has for one of its objects the provision of interlocking and signal mechanism to insure honest measurement and to automatically inform the purchaser of the condition of the dispensing mechanism.

A further object is to provide a dispensing device having interlocking and signal mechanism of improved construction and operation.

The invention is exemplified in the combination and arrangement of parts shown in the accompanying drawings and described in the following specification, and it is more particularly pointed out in the appended claims.

In the drawings—

Fig. 1 is an elevation of a liquid dispenser to which the present invention is applicable;

Fig. 2 is a vertical section substantially on line 2—2 of Fig. 1;

Fig. 3 is a vertical section on line 3—3 of Fig. 2;

Fig. 4 is a vertical section on line 4—4 of Fig. 1;

Fig. 5 is a vertical section on line 5—5 of Fig. 4;

Fig. 6 is a horizontal section on line 6—6 of Fig. 3;

Fig. 7 is a vertical section on line 7—7 of Fig. 6;

Fig. 8 is a vertical section on line 8—8 of Fig. 6;

Fig. 9 is a horizontal section on line 9—9 of Fig. 7;

Fig. 10 is a vertical section on line 10—10 of Fig. 2;

Fig. 11 is a vertical section on line 11—11 of Fig. 1;

Fig. 12 is a horizontal section on line 12—12 of Fig. 3;

Fig. 13 is a fragmentary elevation on line 13—13 of Fig. 8;

Fig. 14 is a vertical section on line 14—14 of Fig. 13; and

Fig. 15 is a horizontal section on line 15—15 of Fig. 5.

The dispensing device, as shown in Fig. 1, is provided with a transparent measuring

receptacle or tank 20 carried upon a supporting pedestal 21. An overflow pipe 22 extends into the tank 20 and fixes the upper surface level of the liquid in the tank. The overflow pipe may be set for any predetermined quantity of liquid, such as five or ten gallons. Indicators 23 are provided to show the amount of liquid in the tank at any time. The tank 20 is formed by a glass cylinder 24 which is seated upon a base casting 25 and made liquid-tight by a suitable sealing means 26. The overflow pipe 22 communicates through a port in the base casting 25 with a return pipe 27. The lower end of the return pipe 27 (Fig. 7) is connected through a valve casing 28 with a pipe 29 by which liquid is conducted through the valve casing 28 back to an underground storage tank or other source of supply. It will be seen from Fig. 7 that the return pipe 27 has free communication at all times through the valve casing 28 and pipe 29 with the storage tank.

As shown in Fig. 10, a discharge pipe 30 extends through a packing gland 31 connected with the base casting 25, the upper end of the pipe 30 opening into the interior of the tank 20. A chamber 32 surrounds the pipe 30 below the packing gland 31 and a connection 33 communicates with the chamber 32 at its inner end and with the filling hose 34 at its outer end. A valve 35 is interposed in the connection 33 and is controlled by a finger lever 36. A casing 37 extends downwardly from the chamber 32 and surrounds the pipe 30, the casing being spaced outwardly from the pipe, as shown in Fig. 10.

The lower end of the casing 37, as shown in Fig. 7, communicates with the valve casing 28. A valve 38 is disposed in the valve casing 28 and is normally closed by a spring 39 against a valve seat 40 to separate the space between the lower end of the casing 37 and the chamber with which the return pipes 27 and 29 communicate. The valve 38 and spring 39 are held in place by a removable cap 41 threaded into the valve casing 28. The discharge pipe 30 extends into the space within the valve casing 28 and is provided with openings 42 and 43 communicating with the interior of the valve casing 28. A rod 44

55

60

65

70

75

80

85

90

95

100

is connected to the lower end of the pipe 30 and extends through a packing gland 45. A lever 46 is pivoted at 47 within the valve casting 28 and is provided with bifurcations 49 underlying a flange 50 on the rod 44. The opposite end of the lever 46 is provided with bifurcations 51 which engage the valve 38. When the pipe 30 is in its lowermost position indicated in Fig. 7, the lever 46 will be held in the position shown in that figure to open the valve 38, for purposes to be explained.

The lower end of the rod 44, as shown in Figs. 4, 5 and 15, is secured to a yoke 52 which is slidably mounted on a fixed guide rod 53. A rack bar 54 is also connected at its lower end to the yoke 52 so that the rack bar and rod 44 are constrained to move vertically in unison with each other. The rack bar 54, as shown in Fig. 8, meshes with a pinion 55 secured to a sleeve 56 journaled on a pin 57 which is carried on the valve housing 28. A crank 58 is attached to the outer end of the sleeve 56 and is positioned outside of the pedestal 21, as shown in Figs. 1 and 8. By rotation of the crank 58 the rack 54 may be raised and lowered and consequently the rod 44 and the pipe 30 will be correspondingly raised and lowered. A vertical stop bar 59 is journaled for rotation within the pedestal 21 and carries adjustable stops 60 spaced longitudinally of the bar and displaced angularly relative to one another. The yoke 52 is provided with a stop finger 61 arranged to contact with the stops 60 when these stops are rotated into the path of movement of the stop finger. A stop plate 62 is carried near the bottom of the bar 59 and is provided with a downwardly extending guide 63 having a vertical guideway therein registering with the notch in the stop plate 62 shown in Fig. 15. When the stop finger 61 is in the position shown in Fig. 15, it may be moved down through the notch in the stop plate 62 and then along the vertical guideway of the guide member 63, the lowermost position of the stop finger 61 being shown in Fig. 5 at the lower end of the guideway. The stop plate 62 is therefore locked against rotary movement so long as the stop finger 61 is in the guideway of the guide 63. The lowermost stop 60 is also mounted on the stop plate 62. The bar 59 may be rotated by means of bevelled gears 64 and a hand-wheel 65. An index dial 66 is connected with the hand-wheel 65 to show which of the stops 60 is disposed in the path of movement of the stop finger 61. As will be hereinafter more particularly referred to the dial 66 is provided with a notched flange 67 for engaging a tongue 68 fixed on the pedestal 21 to accurately locate the stops 60 in the path of the finger 61. A spring 69 yieldingly holds the notched flange 67 in contact with the tongue 68.

The upper end of the rack 54, as shown in

Figs. 3, 6, 8, 13 and 14, extends through an opening in an interlocking yoke 70. A plate 71 is mounted to slide in guides 72 formed on the yoke 70. A pin 73 extends through the upper end of the rack 54 and overlies the top edge of the yoke 70 and sliding plate 71. A rod 74 is fixed to the yoke 70 at its lower end and at its upper end is pivotally connected at 75 to a lever arm 76 pivotally mounted on the pipe connection 33 and constrained by a tooth 76' shown in Fig. 3 to rotate thereon in unison with the valve lever 36. The lever arm 76 is provided with an oppositely projecting arm 77 connected by a link 78 with an indicator 79 pivotally mounted at 80 on the cross-member 80'. When the indicator 79 is in its uppermost or neutral position it will be concealed by a bar 81 formed as a part of and disposed across the frame 81' which is secured to the casing by bolts or the like 82. A second indicator 82 is also pivoted at 80 on the pedestal and is connected by a link 83 with ears 84 on the slide plate 71. The link 83, as shown in Figs. 13 and 14, is threaded at its lower end and is provided with nuts 85 for adjusting the link and slide plate relative to each other. A spring 86 surrounds the link 83 and rests upon a bracket 87 secured to the pedestal housing. The upper end of the spring 86 bears upon a pin 88 carried by the link 83 and resiliently pushes the link upwardly to swing the pointer 82 into a position in the rear of the concealing plate 81. When the rack 54 is in its lowermost position, however, the pin 73 engaging the top edge of the slide plate 71 will hold the link 83 downward in opposition to the spring 86 and retain the pointer 82 in the position shown in Fig. 2. It will be noted that in this position the pointer indicates the words "Discharge to tank" or an equivalent legend, on a plate 89 projecting from the housing 21 adjacent the path of the pointer. The plate 89 at its lower end carries the legend "Discharge to car", or equivalent words.

It will be noted that when the rack 54 is in its lowermost position the rod 44 and the pipe 30 will also be lowered and the valve 38 will be opened, as shown in Fig. 7. This provides free communication from the bottom of the tank 20 through the pipe 30, valve 38, and pipe 29 to the underground storage tank. By lowering the rack 54 the valve 38 is opened and the lower position of the rack also retains the pointer 82 in the position shown in Fig. 2 through the action of the link 83, slide plate 71, and pin 73. This is the normal position of the parts when not in use.

When the operator wishes to supply a quantity of gasoline to a customer he first turns the crank 58 to raise the rack 54. Upon the initial upward movement of the rack 54 the lever 46 will be released and the spring 39 will close the valve 38. At the same time the slide plate 71 will be released by the pin

73 and the spring 86 will expand to move the pointer 82 downwardly so that the pointer will no longer indicate discharge to tank. The operator will continue to raise the rack 54 until the stop finger 61 engages an upper limit stop 90 mounted on the rod 53. This stop is preferably located to arrest the upward movement of the pipe 30 in a position in which the upper end of the pipe will be 10 slightly below the top of the overflow pipe 22. The arrangement and location of the stop 90 in Fig. 4 is for U. S. measurements whereas for Imperial measurement, the stop 90 will be positioned at the top of the bar 59, as 15 shown in Fig. 5. The number of quantity stops 60 are the same for both U. S. and Imperial measurements but the stops 60 for U. S. measurement are spaced closer together which would make the stop 90 for the U. S. 20 measurements much lower than for the Imperial measurements. This accounts for the different positions of the stop 90 in Figs. 4 and 5. The tank is then filled by means of pumping mechanism, not shown, the level to 25 which the liquid rises being determined by the top of the overflow pipe 22. As the liquid rises in the tank it enters and fills the discharge pipe 30, surrounding casing 37 and chamber 32 through small openings 30' 30 drilled through the pipe in position to be located just above the packing gland 31 when the discharge pipe is in its uppermost position. This avoids any possibility of short measure by failure to fill the discharge 35 pipe before gasoline is drawn from the measuring chamber. After the measuring chamber is completely filled the hand-wheel 65 is pulled outward against the resistance of the spring 69 and then rotated until the dial 40 indicates the number of gallons that the customer wishes. At this time the wheel is released and the tongue 68 seats in one of the notches of the finger 67 and holds the dial and bar 59 against rotation. This will bring 45 the proper stop 60 into the path of the stop finger 61. The rack is then lowered until it is arrested by the engagement of the stop finger 61 with the selected stop. After the discharge pipe has thus been properly set the 50 valve lever 36 is moved to open the valve and permit the liquid to flow from the tank through the discharge hose 34 to the customer's car or other receptacle. As soon as the valve is opened in the pipe connection 33 55 the liquid will drain from the tank through the discharge pipe 30, the casing 37, the chamber 32, and pipe connection 33 to the discharge hose. The liquid will continue to discharge until the surface level reaches the 60 top of the pipe 30, thus discharging the quantity determined by the position of the pipe as fixed by the stop 60. To prevent siphoning, the fitting for the hose 34 is equipped with an air vent to atmosphere. 65 The chamber 32 may also be provided with a

vent pipe extending into the glass cylinder 20. As soon as the valve lever 36 is operated to open the valve, the indicator 79 will be swung downwardly to point to the legend "Discharge to car" and will remain 70 in this position so long as the valve is kept open. After the measured quantity of liquid has drained to the car the valve 36 is closed, which will return the indicator 79 to its hidden position. 75

At night or when the station is closed the dial 66 is rotated to bring the notch in the plate 62 in registration with the stop finger 61. The dial may be provided with suitable marking indicating the position for returning the liquid to the storage tank. With the dial set in this return position the hand crank 58 is rotated to lower the rack 54 and the bar 44 to their lowermost position. This will cause the pin 73 to re-engage the slide plate 80 71 and return the indicator 82 to the position shown in Fig. 2. At the same time the flange 50 on the rod 44 will engage the lever 46 and open the valve 38 to permit all of the liquid remaining in the tank to be drained back 85 into the storage reservoir. 90

It will be seen that signal mechanism is provided interlocked with the operating mechanism so that the customer is clearly informed as to the operation of the various parts. The 95 valve for returning the liquid from the tank to the storage reservoir is controlled by the measuring slide pipe and may be opened only by retracting the pipe beyond the extreme measuring position, and when so opened the signal device is automatically operated to indicate that the parts are set to return the liquid to the storage reservoir. The valve for supplying the customer is also interlocked with the return valve in such manner that the 100 return valve cannot be opened while the valve for supplying the customer is opened. So long as the customer's valve is opened the yoke 70 is in its raised position and intercepts the pin 73 to prevent the rack being lowered a sufficient distance to open the return valve. This valve can only be opened after the dial is properly set and after the valve through which the customer is supplied, is closed. In 105 this way the customer is assured of the proper quantity of liquid and by means of the signal mechanism connected with the interlocking arrangement he is at all times definitely informed as to the position of the operating mechanism. 110

I claim:—

1. Dispensing apparatus comprising a measuring tank, a vertically adjustable discharge pipe communicating with said tank, a dispensing valve for controlling the flow of liquid through said discharge pipe to a customer, a signal device connected with said valve for indicating the position thereof, means for raising and lowering said discharge pipe, and means comprising a detent 125 130

for holding said dispensing valve in its closed position when said discharge pipe is in its lowermost position.

2. Dispensing apparatus comprising a measuring tank, a vertically adjustable discharge pipe communicating with said tank, a dispensing valve for controlling the flow of liquid through said discharge pipe to a customer, a drain valve for controlling the flow of liquid from said measuring tank to a storage reservoir, operating mechanism for raising and lowering said discharge pipe, means for automatically opening said drain valve when said discharge pipe is moved to its lowermost position, and a detent connected with said operating mechanism for holding said dispensing valve in closed position when said discharge pipe is in its lowermost position.

3. Liquid dispensing apparatus comprising a measuring tank, a discharge pipe arranged to slide vertically through the bottom of said tank, and a discharge conduit for receiving liquid from said discharge pipe, said discharge pipe having an opening through the wall thereof disposed within said measuring tank when said discharge pipe is in its uppermost position of adjustment.

4. Dispensing apparatus comprising a measuring tank, a discharge pipe arranged to slide vertically through the bottom of said tank and having the upper end thereof open, a packing gland surrounding said pipe at the point where it passes through the bottom of said tank, a receiving chamber surrounding the lower end of said pipe, and a discharge conduit connected with said receiving chamber, said pipe having an opening through the wall thereof in position to be disposed above said packing gland but closely adjacent the bottom of said tank when said discharge pipe is in its uppermost position.

5. In liquid dispensing apparatus, the combination with a measuring tank, of an adjustable discharge pipe for conducting measured quantities of liquid from said tank, a series of quantity stops corresponding to the various quantities to be dispensed in accordance with the adjusted position of said discharge pipe, means for setting the quantity stops, a valve for controlling the return of liquid from said tank to a storage reservoir, means operated by means of said discharge pipe for opening said valve, and mechanism co-operating with said quantity stops for preventing the opening of said valve when any of said quantity stops are in operative position.

6. Liquid dispensing apparatus comprising a measuring tank, adjustable means for discharging measured quantities of liquid from said tank, a series of quantity stops co-operating with said adjustable means to locate the latter in predetermined positions, an index dial, a hand wheel for operating said index dial and positioning said quantity

stops, a drain valve for said tank, means operated by said adjustable means for opening said drain valve, and interlocking mechanism between said adjustable means and said quantity stops for compelling said index wheel to be moved to a predetermined position before said adjustable means can be moved to a position where it will open said drain valve.

7. Liquid dispensing apparatus comprising a measuring tank, a vertical sliding pipe for discharging measured quantities of liquid from said tank, a drain valve, means for opening said drain valve when said pipe is moved to one position of adjustment, and a stop plate having a notch therein for preventing said opening means from operating except when said stop plate is moved where the notch therein will be in a predetermined position.

8. Liquid dispensing apparatus comprising a measuring tank, a vertically adjustable pipe for discharging measured quantities of liquid from said tank, a series of quantity stops for positioning said discharge pipe, a drain valve for said pipe, means operated by said discharge pipe for opening said drain valve when said pipe is moved beyond its discharge positions as determined by said quantity stops, and interlocking mechanism comprising a limit stop associated with said quantity stops for preventing the opening of said drain valve except when said quantity stops are in a predetermined position.

9. Liquid dispensing apparatus comprising a measuring container, a discharge pipe having a liquid-tight sliding connection with said container, means for vertically adjusting said pipe through said connection, stops for positioning said pipe at various heights to permit discharge of predetermined quantities of liquid from said container, means for conducting liquid from said container to be supplied to a customer, a drain valve communicating with the lower portion of said container, means controlled by said pipe for opening said drain valve, and mechanism comprising a notched stop plate associated with said first-named stops to prevent movement of said pipe to a position where the drain valve will be open except when said stop plate is in a predetermined position.

10. Liquid dispensing apparatus comprising a measuring tank, a vertically adjustable pipe for discharging liquid from said tank, means comprising a valve for dispensing liquid from said measuring tank, a drain valve for returning the liquid from said measuring tank to a supply reservoir, means controlled by said pipe for opening said drain valve when said pipe is moved to a predetermined position, means comprising a series of quantity stops for predetermining the various positions of said discharge pipe for dispensing predetermined quantities of liquid from said measuring tank, and means associated with said quantity stops for pre-

venting the opening of said drain valve except when the quantity stops are in a predetermined position and preventing movement of said quantity stops until after the drain valve has been reclosed.

5 11. Liquid dispensing apparatus comprising a measuring tank, a vertically adjustable pipe for discharging liquid from said tank, a series of spirally arranged stops for 70 locating said pipe to predetermine the quantity of liquid to be drawn by said pipe from said tank, a manually operated dispensing valve for controlling flow of liquid from said tank to be supplied to a customer, a drain 75 valve for returning liquid from said tank to a supply reservoir, and interlocking mechanism between said dispensing valve and said drain valve to prevent the manual opening of said dispensing valve when said drain 80 valve is open.

12. Liquid dispensing apparatus comprising a manually operated dispensing valve for controlling dispensing of liquid, an indicating pointer, a screen for said pointer when 85 said valve is closed, an indicating plate having thereon a designation as to discharge of liquid from the dispensing apparatus, and connections between said valve and said pointer for moving the latter from behind 90 said screen to a position where it will point to the designation on said plate when said valve is opened.

13. Dispensing apparatus comprising a visible measuring vessel, means for controlling the dispensing of liquid from said visible measuring vessel, mechanism for predetermining the quantity of liquid to be dispensed from said measuring vessel, a drain valve for controlling return of liquid from 95 100 said measuring vessel to a supply reservoir, mechanism for visibly indicating the discharge of liquid from said measuring vessel during a dispensing operation, and additional mechanism for visibly indicating the draining of said measuring vessel to said supply reservoir while said drain valve is open.

14. Dispensing apparatus comprising a measuring tank, and an adjustable discharge pipe having an intake opening in its upper 105 end, said pipe having an additional opening in its lower portion in communication with the interior of said tank to effect filling of said pipe with liquid when liquid is flowed into said tank.

15. Dispensing apparatus comprising a visible measuring tank, a gauge pipe with its upper end open, and means for adjusting the elevation of the upper open end of said pipe, said pipe having an opening through its wall 110 in position to be disposed above the bottom of said tank when said pipe is in its uppermost position to effect flow of liquid into said pipe when flowing into said tank.

16. Dispensing apparatus comprising a 115 visible measuring vessel, an open ended tube

projecting upwardly into said vessel, means for adjusting the elevation of such open end in accordance with the quantity of liquid to be dispensed from said vessel, means for controlling the flow from said vessel through said tube after the latter has been lowered in elevation in the liquid filling said vessel, and means for limiting the uppermost position of said tube where perforations in the lower portion thereof will establish communication 75 between said vessel and the interior of said tube to fill the latter as the vessel is being filled.

17. In dispensing apparatus, the combination with a measuring tank, of a discharge 80 pipe mounted therein for adjustment in elevation, means comprising a vertical bar for adjusting the elevation of said pipe, a stop finger on said bar, means comprising a series of stops to co-operate with said stop finger to 85 predetermine the position of said pipe, and locking mechanism adapted to co-operate with said stop finger for preventing movement of said quantity stops when said pipe is in a predetermined position. 90

18. In dispensing apparatus, the combination with a visible measuring tank, of a gauge tube extending into the same, means comprising a vertically movable bar for adjusting the elevation of said gauge tube, a valve for 95 controlling the dispensing of liquid from said measuring tank, a lever connected to said valve, a link suspended from said lever, a cross piece suspended from the lower end of said link and mounted for sliding movement over said bar, and a detent at the upper end of said bar above said cross piece in position to engage the latter and hold said link and lever down to hold said valve closed when said bar and said gauge tube are in their lowermost 100 positions. 105

19. In dispensing apparatus, the combination with dispensing mechanism, of means comprising a vertical bar for draining said dispensing mechanism, means comprising a pivoted indicating pointer for visually indicating the draining of said dispensing mechanism, a link suspended from said pivoted pointer, a cross piece suspended from the lower end of said link and slidable over 110 said bar, and a detent at the upper end of said bar for engaging said cross piece to depress said link and move said pointer to its indicating position. 115

20. In dispensing apparatus, the combination with dispensing mechanism, of means for operating the same comprising a vertically movable bar, means comprising a pointer for indicating dispensing of liquid from said dispensing mechanism, means for draining the dispensing mechanism, mechanism comprising another pointer for indicating the draining of the dispensing mechanism, a link suspended from said last-named pointer, a lever connected to said first-named pointer, 120 125 130

an additional link suspended from said lever, a yoke suspended from said additional link, a cross piece suspended from said first-named link and mounted to slide vertically in said 5 yoke, a detent at the top of said bar in position to engage the top of said yoke and also the top of said cross piece, and a spring for holding the top of the cross piece above the top of the yoke and for urging the first-named 10 pointer toward its initial position, said detent at the top of said bar when the latter is moved down acting to engage said cross piece to effect movement of said first-named pointer to a position where it indicates that the dispensing 15 mechanism is being drained, and said detent, by engaging said yoke, acting to hold said second-named pointer against movement toward its position for indicating dispensing of liquid.

20 21. Liquid dispensing apparatus comprising a measuring tank, a vertically adjustable pipe communicating with said tank for discharging measured quantities of liquid therefrom, means comprising a series of spaced 25 quantity stops for arresting said discharge pipe at different positions of adjustment thereof, said pipe being movable to its lowermost position beyond the lowest position fixed by said quantity stops, a drain valve for said 30 tank, means for automatically opening said drain valve when said pipe is moved to its lowermost position, and means for preventing said pipe from being moved to its lowermost position except when said quantity 35 stops are in a predetermined position.

22. Liquid dispensing apparatus comprising a measuring vessel, a discharge pipe having its upper end opening into said vessel, a drain valve connected to the lower end of said 40 vessel, means controlled by said pipe for opening said drain valve, means comprising a series of quantity stops for predetermining the discharge position of said discharge pipe in said measuring vessel, and mechanism comprising a stop plate with a notch in the periphery thereof and a vertical guideway below said notch to prevent the opening of said drain valve except when said quantity stops are in a predetermined position.

50 23. Liquid dispensing apparatus comprising a measuring tank, a vertically adjustable pipe for receiving liquid from said tank, means for adjusting the height of said pipe for predetermining the quantity of liquid to be dispensed from said tank, a manually operated dispensing valve separate and independent from said adjusting means, a drain valve for controlling the return of liquid from said tank to a supply reservoir, and interlocking mechanism between said adjusting means and said dispensing valve comprising a link connected to said dispensing valve and positively pulled by said adjusting means when said drain valve is open.

60 24. Liquid dispensing apparatus comprising

ing a measuring tank, a vertically adjustable pipe for receiving liquid from said tank, means for adjusting said pipe to predetermine the quantity of liquid to be discharged from said tank, a drain valve for controlling return of said liquid through said pipe, a manually operable dispensing valve separate and independent of said adjusting means, and interlocking mechanism between said adjusting means and said dispensing valve comprising a link and a lost motion connection between said adjusting means and said link to permit free operation of said dispensing valve when said drain valve is closed but positively actuating said link to close said dispensing valve and hold the same closed when said drain valve is opened.

70 25. In dispensing apparatus, the combination with a measuring tank, of an adjustable discharge pipe extending into said tank, means comprising a vertically movable bar for adjusting the height of said discharge pipe, a stop finger secured to said bar and movable up and down therewith, a series of 75 quantity stops, a vertical pivoted rod for carrying said quantity stops, means for returning said rod to shift one of said quantity stops to a position below and in vertical alinement with said stop finger, a stop plate secured to the lower portion of said rod, a vertical guide registering with a slot in the periphery of said stop plate in position to receive said finger when said rod is turned to a position where none of said quantity 80 stops is in vertical alinement therewith, and a fixed abutment in vertical alinement with said stop finger when the latter is in said guideway.

85 26. In dispensing apparatus, the combination with a measuring vessel, of a discharge pipe mounted therein for adjustment in elevation, means comprising a vertical bar for adjusting the elevation of said pipe, a stop finger on said bar, means comprising a series 90 of quantity stops to co-operate with said stop finger to predetermine the position of said pipe, locking mechanism adapted to co-operate with said stop finger to prevent movement of said quantity stops when the latter are adjusted to positions where none 95 of them are in vertical alinement with said stop finger, and a fixed abutment in vertical alinement with said stop finger when said quantity stops are held out of vertical alinement with said stop finger so that said discharge pipe may have a free and unobstructed movement from its lowermost position to its uppermost position.

100 27. In dispensing apparatus, the combination with a measuring vessel, of an adjustable discharge pipe extending into said vessel, means comprising a vertically movable bar for adjusting the height of said discharge pipe, a stop finger secured to said bar and movable up and down therewith, a series of 105

quantity stops, a vertical pivoted rod for carrying said quantity stops, means for turning said rod to shift one of said quantity stops to a position below and in vertical alinement with said stop finger, a stop plate secured to the lower portion of said rod, a vertical guideway registering with a slot in the periphery of said stop plate in position to receive said finger when said rod is turned to a predetermined position, and a drain valve operable to open position only when said stop finger moves into said slot.

28. In dispensing apparatus, the combination with a measuring vessel, of a discharge pipe mounted therein for adjustment in elevation, means comprising a vertical bar for adjusting the elevation of said pipe, a stop finger on said bar, means comprising a series of stops to co-operate with said stop finger to predetermine the position of said pipe, locking mechanism adapted to co-operate with said stop finger for preventing movement of said quantity stops when said pipe is in its lowermost position, and a drain valve operable to open position only when said pipe is in its lowermost position and said quantity stops are locked against movement.

In testimony whereof I have signed my name to this specification on this 7th day of April, A. D. 1926.

LEE R. HARTLEY.
